United States Patent Office.

OLIVER H. P. ROSE, OF EAST GREENWICH, RHODE ISLAND.

Design No. 4,170, dated June 21, 1870.

DESIGN FOR BOTTLE.

The Schedule referred to in these Letters Patent and making part of the same.

To all whom it may concern:

Be it known that I, OLIVER H. P. ROSE, of East Greenwich, in the county of Kent and State of Rhode Island, have invented a Design for the Shape of a Bottle; and do hereby declare the following to be a full and correct description thereof, reference being had to the accompanying drawings making part of this specification and to the letters and numbers of reference marked thereon, similar letters and numbers being used in all the figures to denote the same parts.

In these drawings—

Figure 1 is a perspective view of the bottle.

Figure 2 is a horizontal cross-section through the middle of the same.

The nature of my design will be easily understood by the drawings.

I make the bottle of a triangular form, with the

three sides equal, or nearly so, and on one side make a raised bead or border, *a*, inclosing a sort of sunken panel, which is intended to receive the label, indicating the contents of the bottle.

The triangular shape gives a more secure hold to the hand when the bottle is large, and is better for packing than a round one, but the purpose of my design is to afford a distinguishing mark for the protection of my preparation.

I claim the design for a bottle, as represented in the drawings, and described, for the purpose specified.

OLIVER H. P. ROSE.
